SUPPORT FOR ELECTRICAL FIXTURES

Merritt B. Austin, Jr., Kenilworth, Ill.

Application February 14, 1948, Serial No. 8,472

8 Claims. (Cl. 248—27)

1

This invention relates to fixture supports used in building construction, and more particularly to supports known as bar hangers which are adapted to be fastened between joists to support electric outlet boxes, switch boxes, lighting fixtures and the like.

The present invention is concerned with improvements in the bar hanger shown in my Patent No. 2,233,834, issued February 25, 1941, entitled "Support for Electric Fixtures and the Like." In this patent, there is disclosed a bar hanger comprising a single strip of solid, rectangular cross-section bar stock having angularly bent and twisted ends, the bar being adapted to extend laterally between two adjacent joists at an angle determined by the spacing of the joists, and having a prong or spur projecting from one end to provide for temporarily holding the bar in its desired position whereby the permanent fastening thereof is made more convenient.

An object of the present invention is to provide an improved bar hanger of the above type, which is very simple and rugged in construction and satisfactory for all intended uses, while at the same time being quicker and more convenient to install, and extremely economical to produce, and using a minimum amount or weight of inexpensive stock, and requiring but simple and inexpensive fabricating operations.

Another object of the invention is to provide an improved bar hanger as characterized above, which has very effective and economical to-produce means for temporarily holding it in place to permit the permanent fastening thereof to the joists to be done very conveniently, the said means also providing for secure anchorage of the hanger to the joists.

In accomplishing the above objects there is provided, in accordance with the invention and in the embodiment thereof illustrated herein, a bar hanger comprising a sheet metal strip which is formed to have a channel-like cross-section, the strip also preferably having a concave-convex web portion which is shaped or formed to provide a longitudinally extending groove on its outer face and a longitudinally extending rib on its inner face. Intermediate its ends the strip carries a fixture-engaging coupling means which is preferably of the type disclosed and described in my above-referred-to patent. The ends of the channel member are bent in the same direction substantially at right angles to the member whereby the flanges of the strip are outermost, and the ends are also twisted in the same direc-

2

tion through an acute angle about their longitudinal axes. The said bent ends have means, as for example perforations, to receive nails or screws whereby the channel strip may be secured to adjacent, oppositely facing sides of a pair of juxtaposed joists.

Joists which are spaced far apart will receive the channel strip between them at substantially right angles thereto, that is, the strip will extend perpendicularly between the joists. Joists having a closer spacing will require the channel strip to be extended angularly between them whereby acute angles are formed between the strip and joists. The bent ends of the strip preferably make an angle slightly greater than 90° with the outside face of the web, and when the strip is applied to the joists it may be forced or hammered into place between them in such a manner that the edges of the flanges of the strip ends dig into and become embedded in the sides of the joists regardless of the angularity of the strip with respect to said sides.

By virtue of the angle between the strip and bent ends thereof being slightly greater than 90°, sloping or tapering flange edges are presented to the sides of the joists, and these constitute in effect barbs which, while enabling the strip to be readily forced or hammered into position between the joists, yet effectively prevent removal or inadvertent dislodgment of the strip after it has been so positioned. By this organization a quick, convenient and effective temporary positioning of the bar hanger may be had between a pair of juxtaposed joists regardless of variations in the spacing of the joists, thereby making it convenient to drive in the screws or nails whereby the bar hanger is permanently anchored in place, while at the same time the structure utilizes a minimum of stock or weight of metal, and permits of extremely simple and quick fabrication or forming.

The concavo-convex web of the channel strip provides added rigidity to the strip and at the same time the outwardly facing groove in the web acts as a guide whereby the perforations in the bent ends may be readily found for insertion of the nails or screws, by simply sliding the point of the nail or screw along the groove until it meets the desired perforation. Upon the nails or screws being driven in, the flange portions of the bent ends of the channel strip will be forced more deeply into the sides of the joists, and will result in an extremely secure and reliable anchorage.

Other features and advantages will hereinafter appear.

In the accompanying drawings:

Figure 1 is a plan view of an improved bar hanger of the present invention, illustrating one embodiment thereof.

Fig. 2 is a side elevation of the bar hanger shown in Fig. 1.

Fig. 3 is a view showing the application of the bar hanger to joists spaced apart by the maximum distance for which the bar hanger is adapted.

Fig. 4 is a view like Fig. 3 but showing the bar hanger between joists spaced apart by a lesser distance, which may be for example the standard joist spacing.

Fig. 5 is a view like Figs. 3 and 4 but showing the application of the bar hanger to joists having a still lesser spacing.

Fig. 6 is an elevational view of the bar hanger secured to joists which are shown in section, the hanger supporting a fixture such as an outlet box, and

Fig. 7 is a transverse sectional view on line 7—7 of Fig. 2.

Referring to Figs. 1 and 2, the improved bar hanger shown therein as one embodiment of this invention comprises a sheet metal strip 10, preferably formed of steel, carrying a coupling 11 to which a fixture, such as the switch box 12 in Fig. 6, may be secured. The coupling 11 is adjustably positionable on the strip 10, and is preferably of the type shown and described in my patent above-mentioned, having a clamping portion 13 which encompasses the strip 10, and having a stud portion 14 which is secured to the clamping portion 13 by a screw 15, the stud portion 14 being receivable in suitable apertures in various electrical fixtures, outlet and switch boxes and the like.

Referring to Fig. 7, the clamping portion 13 of the coupling has an aperture 13a to receive the strip 10, and a threaded aperture 13b for receiving the clamping screw 15 which passes through the stud 14. Positioning of the coupling 11 is effected by tightening the screw 15, which forces a skirt 13c on the stud 14 to engage the web or flat portion of the strip 10.

In accordance with the present invention the strip 10 is preferably formed of sheet metal, to have a substantially channel-shaped cross-section as shown, with side flanges 16 and 17, and a connecting web portion 18. Preferably the web portion 18 of the strip 10 is concavo-convex, that is, shaped or formed to present a groove 19 on its outer surface, extending longitudinally of the strip, and to present a rib 20 on its inner surface which is complimentary to the groove 19 and also extends longitudinally of the strip.

As shown in Figs. 1 and 2, according to the invention, the ends 21 of the strip 10 are bent in the same direction (upwardly as viewed in Fig. 2) whereby the flanges of the ends are outermost and the said ends form an angle with the outer surface of the web portion 18 which is substantially 90° and preferably slightly greater than 90°, and the ends 21 are also twisted in the same direction about their longitudinal axes and through a small acute angle. The ends 21 are provided with apertures or perforations 22, having their centers lying approximately at the deepest part of the groove 19, for receiving nails or screws by which the strip 10 may be secured between a pair of juxtaposed joists to extend laterally thereof.

By this novel organization and construction an extremely advantageous, quick and convenient

installation of the bar hanger is made possible. Referring to Figs. 1 and 2 it will be noted that the flange portions 16 and 17 of the bent ends 21 present sharp edges or ribs 23 which are facing outwardly, that is, the edges or ribs 23 face away from the center of the strip 10, and the edges or ribs of one bent end face oppositely to the edges of the other bent end, each suitably positioned for embedment in an adjacent joist.

Also, as shown in Fig. 2, the said edges or ribs are sloping or inclined with respect to a perpendicular to the longitudinal axis of the strip 10. This enables the strip to be easily and quickly positioned between a pair of juxtaposed joists such as the joists 24 of Fig. 3, 25 of Fig. 4, 26 of Fig. 5 or 27 of Fig. 6, and to be temporarily held in the position whereby the permanent fastening means, such as screws or nails, may be applied through the perforations 22 in the bar hanger ends 21.

In positioning the strip 10 between the joists 24, 25, 26 or 27, one bent end 21 of the strip may be placed against a side surface of one joist and pressure applied, or blows from a hammer, to cause either one or both of the edges 23 of the flange portions of the said end to become embedded in the side of the joist, the other end of the strip being positioned over the corner of the other joist, such corner being the one formed by the junction of the adjacent side face of the second joist and the outer edge face of said joist. This second end of the strip may then be hammered or otherwise forced inward with respect to the second joist, to cause the edges 23 of the flanges 16 and 17 to cut into the adjacent side face of the second joist. The forcing inward of the said second end is continued until both bent ends of the strip 10 have attained an equal depth along the adjacent side faces of the pair of joists.

It will be seen that the movement by which the second end of the strip 10 is forced inward along the side face of the second joist is facilitated by the slope of the edges 23 of the strip end, which slope is a result of the angle between the end and the strip being slightly greater than 90°. In effect a camming action exists when the second end of the strip is forced inward in this manner, and the end may be cammed inward, the edges of the flanges 16 and 17 functioning as barbs at the extremity of the end 21, and preventing inadvertent withdrawal of the strip or dislodgment from the position in which it is placed. This may be readily seen by inspection of Fig. 6.

Such procedure for temporarily positioning the bar 10 between a pair of joists may be followed regardless of variable spacing between the joists as shown in Figs. 3, 4 and 5. After the strip 10 has been temporarily positioned between the joists, nails or screws may be applied through the perforations 22 whereby the strip 10 is securely anchored in place.

Intermediate its ends 21 the strip 10 may be provided with a perforation 28 and a slot 29 whereby a fixture or outlet box or the like may be screwed to the strip without the use of the coupling 11, the latter being discarded or moved to one side. If the coupling 11 is used, the hollow surface of the web 18 will provide clearance for the inner end of the screw 15. The formation of the web 18 with its hollow outer surface or groove 19 not only provides clearance for the end of the screw 15 but also increases the strength and rigidity of the strip 10, and facilitates the application of the nails or screws since the points

of the latter may be slid along and guided by the groove in the web until they reach the desired perforation.

It will be seen that by the provision of the novel channel-section strip of the present invention, with angularly bent and twisted ends, an extremely advantageous bar hanger is provided which has considerable structural rigidity satisfactory for all intended purposes, is economical of metal, requiring a minimum weight of sheet metal of simple channel-shaped cross-section, and enables a quick and effective temporary positioning of the bar hanger between a pair of juxtaposed joists to be readily accomplished prior to securing of the hanger permanently to the joists.

Variations and modifications may be made within the scope of this invention and portions of the improvements may be used without others.

I claim:

1. A support for electrical fixtures, comprising a bar formed of sheet metal and having a substantially channel-shaped cross-section, the ends of the bar being bent to extend in substantially the same direction at substantially right angles to the bar, with the flanges of said ends outermost, the said bent ends being adapted to be secured to the adjacent sides of a pair of spaced joists to support the bar at an angle with respect to the joists as determined by the spacing between the joists.

2. A support for electrical fixtures, comprising a bar formed of sheet metal and having a substantially channel-shaped cross-section, the ends of the bar being bent to extend in substantially the same direction at substantially right angles to the bar, with the flanges of said ends outermost, and being twisted through an acute angle in the same directions about their longitudinal axes, the said bent ends being adapted to be secured to the adjacent sides of a pair of spaced joists to support the bar at an angle with respect to the joists as determined by the spacing between the joists.

3. A support for electrical fixtures, comprising a bar formed of sheet metal and having a substantially channel-shaped cross-section, the web of the bar being concavo-convex, presenting an inwardly disposed longitudinally extending rib between the flanges of the bar and presenting an outer, hollow surface, the ends of the bar being bent to extend in substantially the same direction at substantially right angles to the bar, with the flanges of said ends outermost, the said bent ends being adapted to be secured to the adjacent sides of a pair of spaced joists to support the bar at an angle with respect to the joists as determined by the spacing between the joists.

4. A support for electrical fixtures, comprising a bar formed of sheet metal and having a substantially channel-shaped cross-section, the web of the bar being concavo-convex, presenting an inwardly disposed longitudinally extending rib between the flanges of the bar and presenting a longitudinally extending groove at its outer surface, the ends of the bar being bent to extend in substantially the same direction at substantially right angles to the bar, with the flanges of said

ends outermost, the said bent ends having apertures in their webs centered substantially at the deepest part of said groove for receiving fastenings to secure the ends to the adjacent sides of a pair of spaced joists whereby the bar is supported at an angle with respect to the joists as determined by the spacing between the joists.

5. A support for electrical fixtures, comprising a bar, the ends of which extend in substantially the same direction at more than right angles to the bar so as to diverge slightly, the said ends being adapted to be secured to the adjacent sides of a pair of spaced joists to support the bar at an angle with respect to the joists as determined by the spacing between the joists; and a rib on each angularly extended end of the bar, said rib extending longitudinally of the end at the outer surface thereof for imbedment into the said sides of the joists and having a sharp outer corner at its end adjacent the end of the bar.

10. 6. A support for electrical fixtures, comprising a bar, the ends of which extend in substantially the same direction at substantially right angles to the bar, the said ends being adapted to be secured to the adjacent sides of a pair of spaced joists to support the bar at an angle with respect to the joists as determined by the spacing between the joists; and a narrow, high and relatively sharp rib on each angularly extended end of the bar, 15 said rib extending longitudinally of the end at the outer surface thereof for imbedment into the said sides of the joists.

7. A support for electrical fixtures, comprising a bar formed of sheet metal and having a sub-

stantially channel-shaped cross-section, the ends of the bar being bent to extend in substantially the same direction at more than right angles to the bar so as to diverge slightly with the flanges of said ends outermost, said flanges having sharp outer corners at each end thereof, the ends of the bar being adapted to be secured to the adjacent sides of a pair of spaced joists to support the bar at an angle with respect to the joists as determined by the spacing between the joists.

45. 8. A support for electrical fixtures, comprising a bar formed of sheet metal and having a substantially channel-shaped cross-section, the ends of the bar being bent to extend in substantially the same direction at more than right angles to the bar, with the flanges of said ends outermost, and being twisted through an acute angle in the same directions about their longitudinal axes, the said ends being adapted to be secured to the adjacent sides of a pair of spaced joists to support the bar at an angle with respect to the joists as determined by the spacing between the joists.
